(57) **CLAIM**

The ornamental design for a stretch mark reduction tool, as shown and described.

DESCRIPTION

FIG. 1 is a top perspective view of a stretch mark reduction tool, showing my new design;

FIG. 2 is a bottom perspective view thereof;

FIG. 3 is a bottom plan view thereof;

FIG. 4 is a top plan view thereof;

FIG. 5 is a side view thereof; and,

FIG. 6 is an end view thereof.

The broken lines in the figures are for environmental purpose only and form no part of the claimed design.
